POSITIVE PIPE TONGS

Filed Sept. 8, 1928

FIG. 5.

ROBERT RAMSAY.

By *Tom J. Bowman*. Attorney.

Inventor.

UNITED STATES PATENT OFFICE

ROBERT RAMSAY, OF SAND SPRINGS, OKLAHOMA

POSITIVE PIPE TONGS

Application filed September 8, 1928. Serial No. 304,824.

This invention relates to a tool for gripping pipes, casings, cylindrical bodies and the like, for the purpose of turning or holding them against turning. The embodiment 5 of the invention disclosed herein is adapted for use especially in the oil fields and the tool when so used bears the technical names of pipe or casing tongs.

Some types of wrenches of the present 10 day are deficient in that part of the force exerted by the operator of the wrench is needed to hold the wrench in its proper position upon the engaged object.

My invention has for its object, first, the 15 provision of tongs which will so grip the work as to allow all of the operator's turning effort to be used to rotate the casing; second, to provide a wrench which is symmetrical about its center whereby it will not 20 tend to twist in the operator's hands when being used; third, to provide symmetrically arranged gripping teeth whereby the engaged work will not be crushed; fourth, to provide a wrench which may be locked in 25 its operative position; and fifth, to provide a wrench which may be readily stood upon its heavy end when not in use.

These objects, together with other objects 30 and corresponding accomplishments, are obtained by means of the embodiment of my invention illustrated in the accompanying drawing in which:

Fig. 1 is a plan view of the wrench in 35 a position just before it has been pushed upon the pipe.

Fig. 2 is a cross sectional view through the head of my wrench on the line 2-2 of 40 Fig. 1, the handle and jaws of the wrench being omitted.

Fig. 3 is a sectional view taken along line 3-3, Fig. 2, one of the jaws being omitted. 45 Fig. 4 is a cross sectional view on line 4-4, Fig. 3, showing the details of the two pivoted joints.

Fig. 5 is a view along line 5-5 of Fig. 1 showing the pawl and ratchet construction which is mounted on the handle whereby the handle is held or locked in an operative position.

Fig. 6 is a view taken along line 6-6, Fig. 4, showing the details of the knuckle joint whereby the pin therein is relieved of shearing stress.

Fig. 7 shows a diagrammatic sketch illustrating the toggle arrangement of the jaws whereby none of the turning force is lost in holding the jaws of the wrench in gripping relationship to their work.

Corresponding parts in all of the figures are designated by the same reference characters.

Referring with particularity to the drawing, the improved wrench, tongs or implement therein shown, comprises in the main 65 a cast iron or steel casing member or head 10, having a handle 20 and two rockers 30 and 40 pivotally mounted thereon. Upon these rockers are respectively pivotally mounted jaws 50 and 60. Both rockers and 70 jaws are identical except one set is right hand and the other set is left hand.

Referring now more particularly to Fig. 1, 10 designates the hollow semi-circular casing or head having holes 11, 12 and 13 extending therethrough. The hole, 12, is the point about which the handle 20 pivots and consequently the ratchet teeth 14, which act in conjunction with a pawl 26 mounted on the handle, are circumferentially formed 80 about this hole.

As shown in Figs. 1, 2 and 3, lugs L, U, G and S are formed integrally with the circular casing 10. These lugs extend horizontally from the casing when the wrench is in a vertical position. When the wrench is not being used it may be stood on its end as the rockers and jaws recede back into the casing 10. Thus the lugs come in contact with the floor and aid in holding 90 the wrench in a convenient position for use.

Handle 20 is pivotally mounted inside of the casing head by means of a pin 15 which passes through a hole 16 in the end of the handle. Cam surfaces 21 and 22 are provided near the pivoted end of the handle as clearly shown in Fig. 3. A small lug 23 prevents excessive movement of the handle 20.

A small chamber 24 is formed integral 100

with the handle and a spring 25 and a plunger 18 are housed therein. This spring is connected to the plunger and is compressed by inward movement of same. Pawl 26 is pivotably mounted upon the handle 20, by means of a stud 27. This pawl has square surfaces 19 and 28 as shown in Fig. 1. Ordinarily the plunger 18 is held in engagement with the shoulder or square surface 19 thus rendering the pawl and ratchet locking means inoperative. However, when the tongs are operated by two or more men it is desirable to lock them in place and this is accomplished by turning the pawl so that surface 28 contacts with the plunger. A small lug 31 provides a means for the release of the pivot.

The hole 11 in the main head provides a seat for the pivot pin 33 and the hole 13 provides a seat for the pivot pin 32. These pins are rigidly attached or made integral with the corresponding rockers 30 and 40. Rockers 30 and 40 are provided with surfaces 34 and 35, respectively, upon that end which is opposite to the camming faces 21 and 22 on the lever 20. These rockers also have holes 36 and 37 in which pins 38 and 39 are placed. As shown in Fig. 6 these holes are in the end portion of the rocker 30 opposite to the camming end. These rockers 30 and 40 are provided with bifurcated ends 41 and 42 which form part of the knuckle joint between these rockers and the jaws themselves.

Jaws 50 and 60 are pivotally mounted upon pins 38 and 39 in the rockers 30 and 40 respectively. Jaw 50 is provided with steel teeth 51 and 52. Jaw 60 is provided with teeth 53 and 54. These teeth are symmetrically placed about the circumference of the work with which they engage. Jaws 50 and 60 are provided with rearwardly extending flanges 55 and 56 which have holes 57 and 58 therein. The pivot pins 38 and 39 hold the jaws in place.

As clearly shown in Fig. 6 the jaws are provided with a curved surface corresponding in shape to the curved surface 42 on the rockers whereby knuckle joints are formed between the rockers and its jaws. Thus the pins 38 and 39 are relieved of any shearing stress during the working stroke of the wrench.

Fig. 7 shows a diagrammatic sketch illustrating in part the operation of the tongs or wrench. This figure shows the rockers 30 and 40 pivotally mounted at the fulcrum points 32 and 33. Thus the outward movement of these two rockers caused by the cam portion on the handle causes the pins 38 and 39 to advance towards the work. However, the construction of this toggle arrangement of the wrench is such that the center of the work, designated by O, is at a short distance back of the point P, which is the

toggle center of this mechanism. Thus, all the force exerted as turning effort will be exerted on the work as the tendency of the wrench will be to move in the direction opposite to that shown by the arrow, A.

The force exerted along arrow A will be opposed by the reaction of the point, C, on the casing, 10, and hence, after the initial positioning movement or tendency toward movement of the wrench will occur.

There are other objects, advantages and features of construction and organization, and details of elements, as will be made manifest in the ensuing description, it being understood that modifications, variations, and adaptations may be resorted to within the spirit, scope and principle of the invention as it is more directly claimed hereinafter.

I claim:

1. A wrench comprised of a semi-circular hollow member having a handle pivoted symmetrically therein, said end of the handle extending inwardly of the hollow member and having cam surfaces thereon, rockers pivotally mounted interiorly of the hollow member and having one of their ends extending adjacent to the cam surfaces whereby they will be operated by the movement of the handle about its pivot, gripping members pivotally mounted on the other ends of the rockers, said hollow member extending past the gripping members when they are in their operative position.

2. In a wrench having a handle and gripping members and intermediary connecting mechanism, the combination of a casing which provides a support for the above referred to elements, said casing extending past the above elements and terminating in a plane which is approximately normal to the axis of the handle when the handle is in its middle or central position.

3. A device of the character described comprised of a hollow casing member open at one side and having another opening at the opposite side, a handle extended through said last named opening and pivotally mounted within the casing member, rockers pivoted in the casing, jaws pivoted to the rockers, said casing extending past or around the rockers and jaws and terminating in a flat portion, said casing member having lugs formed thereon which extend in a direction parallel to the flat portion.

In testimony whereof he affixes his signature.

ROBERT RAMSAY.
